SAFETY PYROTECHNICS

Josef B. Decker, Elkton, Md.

Application January 16, 1934, Serial No. 706,874

11 Claims. (CL. 102—25)

This invention relates to pyrotechnics and particularly to safety pyrotechnic devices of the type adapted to produce either a report, a brilliant flash, a scintillating display, or any combination of these effects.

It is a general object of the present invention to provide a novel and improved pyrotechnic.

More particularly it is an object of the device to provide a pyrotechnic in which the initiating explosion caused by a relatively small quantity of readily detonated explosive is transmitted sympathetically to the main or secondary charge, the explosion of which produces the essential display, report, or the like.

An important feature of the invention consists in making the primary or initiating discharge result from a small quantity of material of relatively high sensitivity, imparting its effect as a booster to discharge the main or secondary explosive of relatively greater quantity and less sensitivity.

When applied to toy torpedoes, the invention is of considerable importance since it permits the use of the minimum quantity of the sensitive explosive material which is discharged by impact, for instance, by the use of gravel mixed therewith, and detonates a large charge of relatively insensitive material so that the possibilities of unintentional explosion are reduced to a minimum and the danger during manufacture is very materially curtailed.

A further important feature resides in the possibility of incorporating the primary and secondary explosives within a single container which can be of considerably less gas-retaining strength than those heretofore used, since its essential purpose is mainly to hold the elements assembled, the explosion resulting from the detonating or boosting of the secondary explosive being so violent and of such short duration that a highly resistant gas enclosing casing is not essential to obtain the maximum loudness of report or dispersion of flash material.

As another important feature of the invention may be mentioned the possibility of totally enclosing the primary or detonating explosive within a cushioning layer of the secondary pyrotechnic material, whereby it is protected against shock or accidental discharge during manufacture, shipping, sale, and handling by the ultimate consumer prior to the very definite and intense shock resulting from finally throwing the device against a solid wall, pavement, or the like.

Other important objects and features of the invention will be more apparent to those skilled

in the art upon a consideration of the accompanying drawing and following specification, wherein are disclosed several exemplary embodiments of the invention, with the understanding, however, that other and corresponding developments are possible as well as combinations and variations of the disclosed embodiments without departing from the spirit of the invention or the scope of the appended claims.

In said drawing:

Figure 1 is a longitudinal central section through a preferred form of toy torpedo constructed according to the present invention;

Figure 2 is a schematic showing of the arrangement of the explosives therein;

Figure 3 is a further schematic showing of another arrangement possible for the explosives;

Figure 4 is a view similar to Figure 1 of a further embodiment of the invention; and

Figure 5 is an additional view, similar to Figure 1, of a still further embodiment of the invention.

In the manufacture of most pyrotechnic devices and particularly fireworks for amusement, display, and industrial purposes, it has been the general practice to bring about the explosion, detonation, or ignition by impacts directed onto the sensitive composition, by friction, or by flame or spark brought into contact with a composition which explodes as the rate of burning increases. Such methods of inducing the explosion have numerous disadvantages, for in the first place there are very serious limitations insofar as the control of the explosion is concerned and, second, the violence of the explosion is very difficult to regulate. These two and other faults have caused tremendous hazards in the industry, particularly in the handling and transporting of the items which are thus very unstable and almost beyond the control of the workers.

In accordance with the present invention, which is broadly applicable to the pyrotechnic field, a novel and unique means of creating the main explosion or rapid burning is made available by the utilization of a principle which has not heretofore been used in the pyrotechnic and allied industries.

In accordance with this invention, a minimum of the pyrotechnic composition or primary explosive is used, and its sole purpose is to be initially ignited by concussion, friction, or the like, to act as a detonator or booster for a pyrotechnic composition which will not, under normal circumstances, ignite either by concussion or friction, and in so doing to produce in this secondary

explosive a discharge of a more violent nature than that which would result from igniting it for instance, by flame or spark.

More specifically, the result is produced by a detonating or fulminating agent which assumes the role of a boosting composition which on its initial explosion sets up a pressure wave of steep front because of its violence, and this wave produces a sympathetic explosion or detonation of the secondary or main charge of pyrotechnic composition which is placed adjacent to, yet separate from, the primary or detonating composition. By reason of the steep wave front produced by the small charge, the violence of the explosion of the secondary charge is materially enhanced so that with a lesser total quantity of explosive material a louder report or brighter flash can be obtained, thereby producing not only a saving in the quantity of material but an increase in the safety of the device, a reduction in its size and cost, and greater safety because of the less sensitive nature of the total composition.

As previously mentioned, the invention is suitable for use with a large number of types of pyrotechnic devices ignited in the various manners common in the art, but for the sake of simplicity it is shown and described only in connection with what is known as a "toy torpedo" of the type adapted to be thrown against a hard surface to be exploded. Obviously it is not the intent to limit the claims to this specific embodiment or the numerous variations thereof but to have the invention limited only by the known prior art.

In Figure 1 what is now the preferred form of the invention is shown. The primary explosive, fulminating composition, or the like is shown at 10, mixed with a suitable quantity of gravel 11 or similar means for causing its detonation as the result of a substantial impact. This mixture is enclosed in a capsule or casing 12 preferably formed of two telescoping cups of pressed paper or the like which may or may not be caused to adhere to each other by the use of a suitable adhesive on the telescoping surfaces.

This inner capsule and its charge are placed within a quite similar outer capsule 14, leaving considerable clearance between the two which is then filled with a composition 15 which is best referred to as a "secondary pyrotechnic composition." It will be noted that this secondary composition is in close proximity to all sides of the capsule containing the initiating charge and completely surrounds it. It thus has two functions, first, to take the initial explosion from the primary or detonating charge and to produce the main report, flash, or whatever the purpose of the device may be and, second, to cushion the more sensitive primary charge and prevent its unintentional explosion as the result of rough handling, accidental dropping, jarring or the like of the device or quantities of the devices during packing, shipping, and so on.

As a specific example it may be stated that the inner capsule may contain the customary toy torpedo explosive which comprises a mixture of antimony sulphide and potassium chlorate, to which sulphur may be added if desired. The relative quantities of these ingredients may be varied to suit, since by changing the ratio of antimony sulphide to potassium chlorate, the degree of sensitivity of the explosive composition can be adjusted.

The outer capsule may or may not have its two parts glued together, as desired. It is filled

with a pyrotechnic composition, in every case less sensitive to explosion by impact, friction, or the like than the material contained in the inner capsule. It may be a pyrotechnic composition of any desired type. For instance, for the sole purpose of a loud report, it may be a perchlorate powder, a potassium perchlorate powder, a nitrate or the like, or any of these combined with color and flash-producing materials, such as aluminum dust, metallic zirconium powder, or any of the other well-known pyrotechnic materials. Where it is intended to have a flash alone without any substantial report other than that produced by the detonating charge, zirconium powder alone may fill the space between the two capsules. The invention is not concerned with the great variations which may be practiced in the loading of the two compartments except that the primary charge be more sensitive and ordinarily of less quantity than the secondary or main charge.

With any quantity limitation on the charges it has been found that a very much louder report, with or without an accompanying flash, color, scintillation, or the like, can be obtained than is possible with the use of the single type explosive of the prior forms of torpedoes.

A torpedo constructed according to the present invention has important advantages not heretofore recited, among which may be specifically mentioned the lessened danger of injury to the user or to bystanders. Because of the extremely small quantity of the initial explosive material, the detonating agent, i. e., the gravel, can be in lesser quantity and of smaller size so that actually five or six pebbles may be sufficient for the purpose of causing the explosion. Likewise the enclosing casings need not have the same gas resisting properties as those used heretofore in order to obtain the same or greater violence of explosion, so that all in all there are practically no parts of any size, weight, or dangerous characteristics to be scattered by the explosion. The enclosing capsules are merely paper or thin cardboard not much greater in weight than Bristol board and are of a fairly pulpy consistency and not at all dangerous when thrown by the explosion.

Since the sole purpose of the containing casing is to offer a slight confinement to the gases and to hold the parts of the torpedo together for handling, it is not made at all sturdy but is preferably treated after assembly by some simple method which will insure the two parts remaining together and which preferably waterproofs, at least to some extent, the whole torpedo. Such a result is readily obtained by spraying the capsules in mass with an adhesive coating, such as water-glass or silicate of soda, which can then be quickly dried by the application of a small quantity of an absorbent dust or powder such as wood flour or the like previously colored to impart a desirable appearance to the torpedo. If the parts of the main capsule are secured together by glue or other adhesive on assembly, the final waterproofing and coloring of the torpedo can be done by treatment with a colored paint containing a heavy pigment which may produce a slight layer, as shown at 16, around the capsule. If the treatment of the exterior of the capsule is done while a quantity of them is being shaken on a vibrating tray, all surfaces will be exposed in a short time and the treatment can be applied with a commercial spray gun.

Another possibility for encasing the capsule, coloring it, and causing the adhesion of the two

parts to each other may be produced by coating the capsule with casein glue in any desired manner, as by dipping, brushing, spraying or the like, and hardening by exposure to formaldehyde gas.

5 Figure 2 shows merely the relative dispositions of the primary and secondary explosives in a torpedo of the type of Figure 1 wherein the primary explosive is totally encased within the secondary explosive and thus cushioned from impact, but 10 having a large area exposed to the explosive wave from the primary explosive.

15 Figure 3 shows a variation of the arrangement of Figure 2 in which the secondary explosive is on the interior and the primary explosive on the exterior, giving the same area of exposure of one to the other but placing the primary explosive where it is more readily ignitable where this may be desirable, as, for instance, in railway torpedoes or the like.

20 Figure 4 shows a further variation in cross-sectional form, in which both explosives are arranged in a single enclosing casing in the form of an open-ended paper cup 20 with the primary explosive and its mixture of gravel in the bottom, 25 as shown at 21, and separated by a suitable septum 22 from the secondary explosive 23 placed in a thicker layer above the septum. Finally a seal or closure 24 of any desired type is applied to insure the retention of the charge in the cup. 30 The exterior of the cup may or may not be treated in the manners described in connection with Figure 1.

A further form of torpedo is shown in Figure 5 which has certain advantages in manufacture. 35 Here the primary explosive 30 is enclosed in a capsule 31 formed of two telescoping paper cups, as described in connection with Figure 1. Included with it is the charge of gravel. The secondary explosive 32 is enclosed in a substantially 40 identical paper cup 33 although the relative heights of these cups may be varied in accordance with the desired ratio of the two explosives, but preferably their diameters are substantially the same. These two capsules are then assembled 45 in any desired relation in a third cup or capsule 35 which may comprise an open-ended tube with suitable plugs or sealing material at the two ends or, as shown, a closed bottom paper cup provided 50 with a sealer 36 at the top which closely confines the two capsules to prevent rattling. As in the case of Figure 4, this form provides a substantial area of exposure of one explosive to the other for satisfactory detonation or boosting after the initial explosion of the primary charge.

55 Various forms of the torpedo different from those already described are, of course, possible to devise, and other types of pyrotechnics may be constructed, taking advantage of the present invention. The main feature of the invention, however, is not in the specific embodiments but in the utilization of the principle of a small quantity of relatively sensitive explosive, adapted to be detonated by any desired method, arranged in close proximity to a much larger quantity of less sensitive pyrotechnical material adapted to be ignited only by detonation from the primary explosive.

Having thus described the invention, what is claimed as new and desired to be secured by 70 Letters Patent is:

1. In a toy torpedo, in combination, an outer casing of substantially gas-tight construction, a primary explosive in said casing, means in the casing to abrade and so ignite said explosive only 75 when the torpedo is violently shocked, a secondary

explosive in said casing, and a wall separating said explosives in such a manner that the second can only be detonated by the first.

2. In a torpedo of the type described, in combination, a closed casing, a small quantity of sensitive explosive and percussion igniting means therefor enclosed in said casing, and means enclosing a larger quantity of less sensitive explosive in close proximity to the first explosive for detonation therefrom.

3. In a pyrotechnic device adapted to be ignited on impact, in combination, a small charge of fulminating explosive, percussive means to ignite the same on impact, a closing casing for said charge and means, a second casing loosely surrounding the first and a charge of pyrotechnic composition of low sensitivity between the two casings.

4. In a torpedo device adapted to be ignited on impact, in combination, a small charge of sensitive explosive, means associated therewith to ignite the same on impact, an envelope closely confining said charge and means, a large casing of gas-tight material loosely surrounding said envelope and pyrotechnic composition filling all 20 the space between the casing and envelope and cushioning the explosive on all sides.

5. In a torpedo of the type described, in combination, at least two explosives, one of small 30 quantity, high sensitivity and low power, another of larger quantity, low sensitivity and great violence, means associated therewith to ignite the first explosive by impact and means so confining the two explosives separately that the second may 35 only be detonated in sympathy with the first.

6. In a torpedo of the type described, in combination, at least two explosives, one of small quantity, high sensitivity and low power, another of larger quantity, low sensitivity and of 40 great pyrotechnic value, means associated with the first explosive to ignite the same upon impact, means enclosing the first explosive and said means, a container for the second explosive, and means positioning it so that the second explosive will be detonated by the first explosive.

7. In a torpedo of the type described, in combination, explosive sensitive enough to be ignited by impact, abrasive means mixed with said explosive, an envelope for said mixture, a larger quantity of a less sensitive explosive completely surrounding said envelope and arranged to be ignited only by detonation, and a substantially 50 gas-tight casing for the whole assembly.

8. In a torpedo of the type described, in combination, explosive sensitive enough to be ignited by impact, gravel mixed with said explosive, a tight envelope for said mixture, a quantity of pyrotechnic composition of low sensitivity against 60 a wall of said envelope and adapted to be ignited only by detonation and a gas-tight casing enclosing the envelope and composition.

9. In a toy torpedo, in combination, an envelope formed of telescoping paper cups, a sensitive explosive and gravel therein, a second and larger envelope of telescoping paper cups loosely surrounding the first envelope, a charge of pyrotechnic composition filling the space between the two envelopes and means to secure the parts of the 70 second envelope together.

10. A toy torpedo of the type described and including a powdered primary explosive, gravel intimately mixed therewith to ignite the same on impact, a secondary explosive of great violence 75

close to the primary explosive, a flame-tight partition separating said explosive, and a casing for both explosives of only sufficient strength to confine them during manufacture and shipment.

5 11. In a torpedo adapted to be exploded by impact, in combination, a small charge of sensitive explosive composition, abrasive means to ignite the same on impact, a charge of pyrotech-

nic composition in greater quantity than said sensitive explosive, flame-tight means separating the explosive and pyrotechnic compositions whereby the second is exploded only by sympathy from the first, and a closed casing around 5 all of said elements.

JOSEF B. DECKER.
